UNITED STATES PATENT OFFICE.

CHRISTEN MATTISON, OF MINNEAPOLIS, MINNESOTA.

CHAMFER-CUTTER.

SPECIFICATION forming part of Letters Patent No. 411,506, dated September 24, 1889.

Application filed May 13, 1889. Serial No. 310,542. (No model.)

To all whom it may concern:

Be it known that I, CHRISTEN MATTISON, a citizen of the United States, residing at Minneapolis, in the county of Hennepin and State 5 of Minnesota, have invented certain new and useful Improvements in Chamfer-Cutters, of which the following is a specification.

The object of this invention is to provide improved means for cutting a chamfer or bevel upon strips or pieces of wood which are designed to be used in the finish of buildings, and in the same operation finish the ends of the same in any desired ornamental design.

15 In putting on the finish of buildings it is often desirable to use strips or pieces of wood having a bevel or chamfer cut upon the edge thereof for a portion or portions of its length. It has heretofore been customary to cut the 20 chamfer in such cases by means of machinery, but to finish the ends of the same with hand-tools. It is only by exercising a great deal of care that such work can be done at all by hand, and it is necessarily slow and laborious. By the machine which I employ and 25 which is hereinafter particularly described, such chamfers or bevels can be rapidly made, and their ends can be given any desired ornamental finish.

30 In the accompanying drawings, forming a part of this specification, Figure 1 is a side elevation of my improved machine, the frame being shown in section. Fig. 2 is an end elevation of the same with the portion of the 35 frame broken away. Fig. 3 is a side elevation of the cutter-head and cutters. Figs. 4 and 5 are detail views of one of the cutters. Fig. 6 is a plan view of a strip of wood having chamfers or bevels, such as may be formed 40 by my machine. Fig. 7 is a detail section on line $x-x$ of Fig. 6. Fig. 8 is a view similar to Fig. 6, showing an ornamental finish at the end of the bevel or chamfer.

In the drawings, 2 represents the frame of 45 the machine, which may be of any suitable construction. Upon this frame is mounted in suitable bearings a shaft 3, which is adapted to be driven from any suitable source of power. Secured upon this shaft is a cutter-head 50 50 which may be fastened upon the shaft by any

suitable means. This cutter-head is provided upon its periphery with two series of plane surfaces, which are inclined toward the axis of the cutter-head. These inclined surfaces are arranged alternately and inclined in opposite directions. A series of knives 9 are secured upon the plane surfaces upon the periphery of the cutter-head. Each of the knives 55 9 consists of a main portion having an inclined cutting-edge and a wing or projection 60 11, extending at an angle from the main portion of the cutter, and provided also with a cutting-edge 12. These knives are made right and left hand, one set of them being secured to one of the series of inclined surfaces and the other 65 to the oppositely-inclined surfaces. The cutting-edges of the knives are thus oppositely inclined, and the cutting-edges of the wings project on each side beyond the head and are also oppositely inclined. 70

The material to be beveled or chamfered is placed upon the frame of the machine, and is preferably brought against a suitable gage-plate 17, and the cutter is driven at requisite speed. The cutters strike the edge of the material and cut a chamfer or bevel thereon. As the knives are oppositely inclined, and as they are provided with the oppositely-inclined wings, which are also provided with cutting-edges, each knife will make a drawing cut 80 across the corner of the wood, and the two knives together will cut a bevel or chamfer of the width of the head, the ends of which will be cut by the wings on the knives. In Fig. 6, 18 represents the bevel or chamfer, 85 and 19 the ends thereof, which are cut by the wings on the knives. By moving the wood in either direction across the cutter-head the bevel will be continued for any desired length, and the end thereof will always 90 be finished by the incline 19. By forming the knives with wings having curved or rounded cutting-edges the ends of the bevel may be given curved or rounded ends—such, for example, as indicated at 20 in Fig. 8. Any suitable shape may be given to the cutting-edges of the wings, and thus any suitable finish may be given to the ends of the chamfers. 95

I claim as my invention—

The combination, with the cutter-head pro- 100

vided with the oppositely-inclined and alter-
nately-arranged plane surfaces upon its pe-
riphery, of the right and left hand knives pro-
vided with the inclined cutting-edges, and
5 with the inclined wings projecting beyond
the body of the knives, and provided also with
an inclined cutting-edge, substantially as de-
scribed.

In testimony whereof I have hereunto set
my hand this 8th day of May, 1889.

CHRISTEN MATTISON.

In presence of—
T. D. MERWIN,
A. C. PAUL.
